UNITED STATES PATENT OFFICE.

CARL A. WENDELL, OF ROCKVILLE CENTER, NEW YORK.

CRUSHER.

1,366,985.

Specification of Letters Patent.

Patented Feb. 1, 1921.

Application filed August 1, 1919. Serial No. 314,732.

To all whom it may concern:

Be it known that I, CARL A. WENDELL, a citizen of the United States, residing in Rockville Center, Long Island, New York, 5 have invented certain new and useful Improvements in Crushers, of which the following is a specification.

This invention relates to a machine particularly adapted for crushing coal, but also 10 adaptable for crushing ore and other materials such as cement clinkers, lime for hydrated lime plants, packing house by-products such as bone, limestone and also materials that have a tendency to pack such 15 as ice, phosphate rock, gypsum, etc.

In the embodiment of the invention shown the crusher comprises a rotatably mounted frusto-conical drum which is surrounded by a fixed shell so shaped and supported relatively to the drum that the space between its inner surface and the outer surface of the drum gradually decreases in area from the inlet end to the discharge end of the crusher. The crusher has a discharge outlet extending practically all the way around the lower 25 end of the drum as well as one extending the full length of the side of the drum.

One of the objects of the invention is to provide a crusher having a much greater 30 normally active crushing surface than the ones now generally in use, another object is to provide a crusher in which the formation of fines is reduced to a minimum, another object is to provide a crusher which for a given size will give a larger output than that attainable with prior constructions, a further object is to provide a crusher having an outlet all around the circumference of the crushing drum and also an outlet all 35 along one of the sides thereof, a further object is to combine and organize the various elements herein shown and described so as to effectively perform the functions set forth, other objects will be apparent from 40 the following description and claims when read in connection with the accompanying drawings in which—

Figure 1 is a central longitudinal vertical section through the crusher, the driving 45 mechanism and parts of the supporting structure being shown in elevation;

Fig. 2 is a section on the line 2—2 of Fig. 1, the supporting structure being omitted;

Fig. 3 is a fragmentary section on the 50 line 3—3 of Fig. 2 showing both of the discharge outlets.

Referring to the drawings a drum A is

keyed or otherwise secured to a shaft B which shaft is driven by bevel gears C and C' which in turn are driven from a pulley 60 D which pulley is connected by means of a breaking pin d to its shaft E, this pin being of such size that it will be sheared off in the event of the material becoming wedged in the crusher. The shafts B and E are 65 supported in suitable bearings carried by frames F and G which frames are supported on suitable girders H.

The breaking drum A is of frusto-conical shape with its small end uppermost, its outer 70 surface is covered by plates a which may be removably secured to enable their being replaced after they are badly worn or in the event of their breakage. These plates are roughened either by providing ridges or 75 projections on their outer surface so as to enable them to effectively grip the lumps of material being crushed.

The crushing drum A is surrounded by a fixed shell J having a lining of plates j detachably secured to its inner surface, these plates having either ridges or projections formed on their inner surface similar to those formed on the crushing drum. The bottom edge of the lining j is concentric 85 with the drum A and spaced a short distance away therefrom thus forming a discharge outlet K which extends practically all the way around the periphery of the drum. The upper edge of the shell J at the 90 feed end L is substantially normal to the lower edge as shown in Figs. 1 and 2. This upper edge gradually extends inward toward the axis of the drum as it approaches the outlet end M, this upper edge being 95 substantially in the form of a spiral as shown in Fig. 2. A baffle plate l is secured to the shell J to guide the material to be crushed.

The inner surface of the shell is substantially in line from the top to the bottom edge thereof and it will, therefore, be appreciated that this surface is gradually inclined inwardly toward the axis of the drum from the inlet to the outlet end. As thus 100 arranged the cross-sectional area of the space between the inner side of the shell and the outer side of the drum will be greatest at the inlet end L and will be of a minimum size at the outlet M, the cross-sectional area 105 of the intermediate space between said shell and drum gradually decreasing at different points toward the outlet end of the shell.

The crushing drum A is rigidly secured

to the shaft B by a key and pin or other suitable means and the bevel gear C is splined on the shaft B to permit an endwise movement of the shaft. The lower end of 5 the shaft B is slideable in a bearing *g* formed on the frame G and rests on an anti-friction bearing *b* which may be adjusted vertically by means of a screw N which is threaded in a cap O secured to the lower part of the 10 bearing *g*, a lock nut *n* being provided to secure the screw N in its adjusted position. By this means it will be apparent that the size of the discharge outlets M and K may be varied thereby determining approximately 15 the size to which the material will be crushed.

In operation the material to be crushed is fed in at the point L, the baffle plate *l* serving to prevent the rough uncrushed stock 20 from escaping and mixing with the crushed material discharged from the outlets M and K. The drum is rotated in the direction of the arrow *z* and the lumps are carried downwardly and around the crusher, the larger 25 lumps being gradually reduced in size, the broken pieces being permitted to drop to the lower level for further crushing and the fines immediately dropping through the discharge outlet K.

30 Practically the entire outer surface of the drum A and the inner surface of the shell J is effectively used in normal operation when crushing the material. The discharge outlet K formed at the bottom of the crusher practically surrounds the drum and the second 35 discharge outlet M extends the entire length of the drum. With such a structure the small particles or fines can immediately drop to the lower levels and be discharged 40 through the outlet K without choking up the crusher or causing the pulverization of said fines as happens in the typical forms of crushers heretofore used. My improved crusher provides a very large effective crushing 45 surface and is so designed as to apply the crushing action gradually so that the lumps are reduced progressively to a smaller size while traveling forwardly and downwardly around the apparatus. While this 50 gradual crushing action takes place the smaller pieces are always allowed to get away from the larger material until it has been reduced to the size wanted and lumps of the desired size are continually discharged 55 all around the bottom opening K of the crusher as well as all along the up and down opening M.

It is well known that when washing coal, the fines are not benefited by washing to the 60 same extent as the coarser sizes, and that the coal, say below $\frac{1}{16}$ inch, is, in fact, detrimental to good washing. In some coals these fines are the very best coal and can, therefore, be screened off before the washing 65 process and added dry to the product later

on, but in many coals these fines are the highest in ash and sulfur.

When the run-of-mine coal has to be crushed rather fine in preparation to washing a very large percentage of this consists 70 of coal below $\frac{1}{16}$ inch which is not benefited to any extent by washing, and besides in any case is undesirable as it has to be taken care of in the form of sludge when clarifying the water for re-use, all of which is expensive, 75 and results in the loss of a considerable quantity of fine coal.

The ordinary two-roll or one-roll crushers are so constructed that all the coal—fines as well as lumps intimately mixed together—have to pass through a more or less narrow opening and with no means for letting the fines already crushed escape with the result that the fine coal is crushed up 80 still finer.

The construction of the ordinary two-roll crusher is also such that only a very small part of the surface of the rolls is actually engaged in work and all the coal has got to be treated by this small surface or the immediate section around the opening between the rolls, which in itself also facilitates the choking up of the crusher. The length of this opening thus to a great extent decides the tonnage which can be treated per hour. 95 Comparing a typical two-roll crusher having a roll diameter of three feet and a length of three feet the maximum effective crushing surface will be approximately six square feet and the discharge opening will be three 100 feet in length. A crusher built according to my invention having the drum three feet high and a diameter of three and four feet respectively at the top and bottom would have an effective crushing surface of approximately thirty square feet and a discharge opening of about fifteen feet. It will, therefore, be apparent that the output in an equal period of a crusher built in accordance with my invention will greatly exceed 105 that of the forms of crushers now in use.

Though I have described with great particularity the specific embodiment of the invention shown it is not to be construed that I am limited thereto as changes in construction and substitution of equivalents may be made by those skilled in the art without departing from the invention as defined in the appended claims.

What I claim is—

1. A crusher comprising a frusto-conical drum having its small end uppermost, means for rotating said drum about a substantially vertical axis, a shell surrounding 125 said drum, the lower edge thereof being concentric with and spaced away from said drum to form a discharge outlet of uniform size substantially around said drum, the inner surface of said shell being inclined at 130

different angles to said drum at different points in its perimeter.

2. A crusher comprising a frusto-conical drum having its small end uppermost, means for rotating said drum about a substantially vertical axis, a shell surrounding said drum, the lower edge thereof being concentric with and spaced away from said drum to form a discharge outlet of uniform size substantially around said drum, the inner surface of said shell being inclined at different angles to said drum at different points in its perimeter and means for effecting a relative adjustment between said drum and said shell to vary the size of the discharge outlets.

3. A crusher comprising a frusto-conical drum having its small end uppermost and arranged to be rotated on a substantially vertical axis, a shell surrounding said drum, the lower edge of which is substantially concentric with said drum and the upper edge of which starts at a point normal to the lower edge and gradually extends inward as it progresses around the drum, the inner surface of said shell having projections formed thereon, the tops of which are substantially in a line extending from the top to the bottom edges of said shell.

30 4. A crusher comprising a frusto-conical drum with a roughened outer surface having its small end uppermost, driving means for rotating said drum, a fixed shell having a roughened inner surface surrounding the greater portion of said drum, the inner surface of said shell being substantially parallel with the axis of said drum at the end where the material is fed to the crusher and

gradually inclined toward the drum as it approaches the discharge end where said surface is substantially parallel with and spaced away from the inclined side of the drum, the lower edge of said shell being substantially concentric with and spaced away from the lower portion of the drum to form a discharge outlet of uniform width substantially all the way around the drum, and means for adjusting said drum relatively to said shell to vary the size of the discharge outlets.

5. A crusher comprising a frusto-conical drum with a roughened outer surface having its small end uppermost, driving means for rotating said drum, a fixed shell having a roughened inner surface surrounding the greater portion of said drum, the inner surface of said shell being substantially parallel with the axis of said drum at the end where the material is fed to the crusher and being gradually inclined toward the drum as it approaches the discharge end where said surface is substantially parallel with and spaced from the inclined side of the drum, the lower edge of said shell being substantially concentric with and spaced away from the lower portion of the drum to form a discharge outlet of uniform width substantially all the way around the drum, a structure for supporting said shell and said driving means, and means carried by said structure for adjusting said drum axially to vary the size of the discharge outlets.

In witness whereof, I have hereunto signed my name.

CARL A. WENDELL.
